(57) **CLAIM**

I claim the ornamental design for a threaded shoe lace, as shown and described.

DESCRIPTION

FIG. 1 is a perspective view of the threaded shoe lace; the tonal pattern shown in this FIG. 1 and other FIGS. 2–4 represents color contrast, and is not intended to represent any particular color or combination of colors;

FIG. 2 is an end view of the threaded shoe lace;

FIG. 3 is a first elevational view of the threaded shoe lace; and, FIG. 4 is a second elevational view of the threaded shoe lace.
